FIG. 1

FIG. 2

FIG. 3

FIGURE 1 is a front perspective view of an optical reader, showing our new design;

FIGURE 2 is an elevational view taken from one side thereof, the opposite side being a mirror image of the side shown; and

FIGURE 3 is a rear elevational view thereof.

The bottom of the optical reader is substantially flat except for several small furniture-protector pads thereon.

We claim:

The ornamental design for an optical reader, substantially as shown and described.
